UNITED STATES PATENT OFFICE.

BERNARD OWEN, OF GREENWICH, LONDON, ENGLAND.

TOY GUN.

1,365,187.

Specification of Letters Patent. Patented Jan. 11, 1921.

Application filed April 24, 1920. Serial No. 376,350.

To all whom it may concern:

Be it known that I, BERNARD OWEN, subject of the King of Great Britain and Ireland, residing at 31^a South street, Greenwich, in the county of London, England, have invented certain new and useful Improvements in Toy Guns, of which the following is a specification.

This invention relates to improvements in toy guns, or the like and is particularly intended to imitate or represent a machine or quick firing gun.

According to the invention, the apparatus is constructed for use with explosive caps formed in continuous strips. The device comprises a body portion or casing within or on which the firing mechanism, and the mechanism for feeding forward the explosive strip is mounted.

The firing mechanism comprises a striking hammer fixed to a spindle rotatably supported at the top of the casing and adapted to be moved rearwardly against the action of a spring by a cam mounted on one end of a cocking or crank-handle. The feeding mechanism comprises a slidable member having mounted thereon a spring controlled rocking pawl adapted to frictionally engage the explosive cap-strip when moved in one direction, and to slide freely over the surface of said strip when moved in the opposite direction. This slide, which is suitably guided in its movement carries a projecting member extending into the path of a second cam fixed to the cocking handle spindle. The cams on the spindle are so arranged that the striking hammer is first drawn back to firing position and thus releases the strip and the feeding mechanism is then moved forward to feed the strip forward the required distance, after which the hammer being returned to its normal position by its spring, the cap is fixed and the strip is gripped thereby during the return movement of the feeding mechanism to its normal position.

The casing or framing carries at its front end a barrel or the like which may be enclosed by an outer casing. The inner barrel carries on one side a longitudinal slot from which projects the operating member or handle of a spring-controlled ejector or plunger adapted to eject a bullet or the like from the barrel at or about the moment the explosive cap is fired. This ejector is drawn back by hand each time the cocking handle

is rotated and the body or casing carries a pivotally mounted cam-plate or locking member adapted to engage the operating member of the ejector when the latter is drawn back to its rearmost position and is released by one of the cams on the cocking-handle spindle when the latter is rotated.

In order that the invention may be readily understood I will now describe the same with reference to the accompanying drawings which show the invention applied to a machine or quick-firing gun, from which other applications thereof will be readily understood.

Figure 1 is a side view partly in section taken from the side thereof on which the cocking or crank handle is located.

Fig. 2 is a longitudinal sectional elevation of the body or casing.

Fig. 3 is a rear elevation, while

Fig. 4 is an outside elevation seen from the opposite side to the view shown in Fig. 1.

Referring to the drawings 1 is the body or casing portion of the apparatus having at or near its lower end a chamber or inclosure 2 closed by a slidable or rotatable door or lid 3 pivoted to the casing at 4. The chamber may be provided with a central pin or stud 5 on which the continuous strip of explosive caps 6 in the form of a reel or spool is placed. The strip passes from the chamber 2 at or near the bottom thereof from whence it is guided upwardly by the side of the partition or wall 7 of the casing. Mounted adjacent the strip is the feeding mechanism comprising a vertically slidable member 8 having two or more projecting pins or studs 9 projecting from each side thereof and adapted to move in vertical guide slots 10 formed in the side members of the casing. One of said pins carries an extension 11 on the side projecting into the path of a rotatable cam 12 hereinafter described. The slidable member 8 carries at its upper end a spring controlled feeding pawl or arm 13 pivoted at 14 to the slide 8 and arranged so that when the sliding member is moved upwardly, the outer free end of the pawl frictionally engages the cap-strip 6 and carries same with it during its upward movement. The pawl 8 lies in such a position that when engaging the strip, its free end is in a slightly higher plane than its pivoted end as shown in Fig. 2, thus causing a wedge-like engagement with the strip during its upward movement, while during

the downward movement of the slidable member, the pawl 13 slides freely over the surface of the strip. The pawl 13 is normally maintained in engagement with the cap-strip by a spring 15 secured to the sliding member, while the latter is normally maintained in its lowermost position by a spring 8^a.

The means for exploding or firing the caps 10 in the cap-strip 6 comprises a striking hammer 16 fixed to a spindle 17 rotatably mounted between the rearwardly extending side member of the casing 1. One end of the spindle 17 carries two laterally projecting 15 arms 18 and 19. The arm 18 has attached to its end a spring 20 secured at its opposite end to the casing 1 at 21, while the arm 19 has an outwardly projecting extension 22 lying in the path of a cam 23.

20 The forward end of the body or casing 1 is provided with a barrel or the like 24, which may, if necessary, be inclosed or partially inclosed by an outer casing 25 to represent a water jacket. Mounted within the 25 barrel 24 is an ejector or plunger 26 normally maintained toward the forward end of the barrel by a spring 27 encircling the rod or the like 28 pivotally or otherwise attached to the plunger. The rear end of this rod 30 is formed with or has attached thereto an outwardly projecting operating handle or arm 29 projecting through a longitudinal slot 30 formed in one of the side members of the body or casing 1. This slot is inclined 35 upwardly toward its rear end as shown in Fig. 1, and at its extreme end is provided with a lateral extension 31 into which the operating handle or arm 29 is moved when the plunger is drawn back to its most rearward position to be retained thereby. Mounted adjacent the slot 31 is a freely rotatable cam-plate or the like 32 pivoted at 33 to the casing. The upper end of the cam-plate has a curved cam face 34 adapted to 40 engage the operating handle 29 when rotated. The lower portion of the cam-plate has a downwardly and outwardly projecting extension 35 lying in the path of the cam 12 while its movement about its pivot is limited 45 by a guide or gate 36.

The barrels 24 and 25 are provided with a recess or aperture 37 arranged immediately in front of the plunger 26 when the latter is moved to its rearward position and 50 serves to enable a bullet or projectile to be inserted into position to be ejected from the barrel by the release of the ejector.

The cams 12 and 23 for operating the firing mechanism, the feeding mechanism for 55 the cap-strip and the ejector are mounted fixedly on a spindle or shaft 38 mounted rotatably in the body of the casing. One end of the spindle has secured thereto a cocking-handle or crank-handle 39 by means of 60 which it may be rotated. The cams 12 and

23 are so arranged relatively to one another that on rotation of the cocking handle 39 in the direction indicated by the dotted line and arrows in Fig. 1, the cam 23 first engages the arm 22 of the striking hammer 70 spindle 17 and commences to move the hammer rearwardly toward its firing position and thereby releasing the strip 8 after which the cam 12 engages the extension 11 of the vertically sliding member 8 to move the 75 same upwardly to feed the cap-strip forward.

The base of the casing 1 is provided with a screwed stud or pin or the like 40 to which a tripod or other suitable form of gun 80 mounting 41 may be secured. The top rear portion of the casing is provided with a suitable recess or aperture through which the spent strip passes, while the body may further have attached thereto a screen or 85 the like 42.

The operation of the apparatus is as follows:—

The cap strip is placed in position on the pin or studs 5 within the chamber 2, the 90 end of said strip being fed upwardly between the feeding pawl 13 and the frame member 7 and between the latter and the striking hammer 16, the strip being adjusted until the head of the hammer engages one 95 of the explosive caps formed in the strip. The apparatus is now ready for firing.

On rotation of the cocking-handle 39 attached to the spindle 38, the cam 23 first engages the projection 22 on the end of the 100 arm 19 of the spindle 17 to draw back the striking hammer 16. This movement of the hammer releases the strip 8 and enables same to be fed forward by the feeding mechanism. The extension 11 of the sliding 105 member 8 is now engaged by the cam 12 and moved upwardly. The spring controlled pawl frictionally engages the cap-strip 6 and carries the latter with it during its upward movement, whereby the strip is 110 fed forward through the distance between two caps in the cap-strip. On further rotation of the cocking handle the top of the cam 23 releases the striking hammer which is returned by the spring 30 to fire the cap. 115 On the cocking-handle being slightly further rotated, the cam 12 releases the sliding member 8 which is returned by its spring 8^a, and during said movement the spring controlled pawl 13 slides freely over the cap strip, the latter being now retained against movement by the striking hammer 16. The cocking-handle is now further rotated and the cam 12 engages the extension 35 of the pivotal cam-plate 32 rotating same in an 120 anti-clockwise direction as seen in Fig. 1.

This movement causes the cam face 34 to engage and move upwardly the operating handle of the ejector until said handle registers with the longitudinal inclined slot 30 130

whereby the plunger is freed and is forced outwardly by the spring 27, to eject the bullet or projectile previously inserted into the aperture 37. The operation is continued 5 as will be readily understood, the plunger 26 being drawn back by hand to reengage the slot 31.

The operating mechanism may, if necessary, be entirely inclosed within the body 10 portion of the casing.

It will be readily understood that various modifications in the details of construction the sequence of operations and arrangements 15 of parts may be made without departing from the principle of the invention.

I claim:—

1. In a toy gun for firing explosive caps arranged in continuous strips, a vertically 20 slideable member, a spring to control said member, a spring controlled pawl on the slideable member adapted to engage the cap strip, to feed the caps, when moved in one direction and to slide freely over them in the other direction, mechanism for firing the 25 caps, mechanism for ejecting a projectile and a rotatable crank or cocking-handle adapted to operate the three mechanisms.

2. In a toy gun for firing explosive caps arranged in continuous strips, a vertically 30 slideable member, a spring to control said member, a spring controlled pawl on the slideable member adapted to engage the cap strip, to feed the caps, when moved in one direction and to slide freely over them in the other direction, a hammer for firing the 35 caps, a spring controlling this hammer, mechanism for ejecting a projectile and a rotatable crank or cocking-handle adapted to operate the three mechanisms, a spindle 40 to the cocking-handle, a cam on this spindle, and a projection on the spring controlled hammer adapted to be engaged by the cam to move the hammer to the firing position.

3. In a toy gun for firing explosive caps 45 arranged in continuous strips, a vertically slideable member, a spring to control said member, a spring controlled pawl on the slideable member adapted to engage the cap strip, to feed the caps, when moved in one direction and to slide freely over them in the other direction, mechanism for firing the 50 caps, a spring controlled plunger in the barrel of the gun, a handle movable in a longitudinal slot, a cam to release the plunger so as to eject a projectile after the feeding mechanism has been released, and a rotatable 55 crank or cocking-handle adapted to operate the three mechanisms.

4. In a toy gun for firing explosive caps 60 arranged in continuous strips, a vertically slideable member, a spring to control said

member, a spring controlled pawl on the slideable member adapted to engage the cap strips, to feed the caps, when moved in one direction and to slide freely over them in the other direction, a hammer for firing the caps, a spring controlling this hammer, a spring controlled plunger in the barrel of the gun, a handle movable in a longitudinal slot, a cam to release the plunger so as to 70 eject a projectile after the feeding mechanism has been released, and a rotatable crank or cocking-handle adapted to operate the three mechanisms, a spindle to the cocking handle, a cam on this spindle, and a projection on the spring controlled hammer adapted to be engaged by the cam to move the hammer to the firing position.

5. In a toy gun for firing explosive caps arranged in continuous strips, a vertically 80 slideable member, a spring to control said member, a spring controlled pawl on the slideable member adapted to engage the cap strip, to feed the caps, when moved in one direction, and to slide freely over them in the other direction, mechanism for firing the 85 caps, a spring controlled plunger in the barrel of the gun, a handle connected to the plunger, a slot in the body or casing and a recess in the end of this slot in which the 90 handle on the plunger engages, a rotatory cam-plate adapted to release the handle from the recess in the slot in which it engages so as to eject a projectile after the feeding mechanism has been released and a rotatable 95 crank or cocking-handle adapted to operate the three mechanisms.

6. In a toy gun for firing explosive caps arranged in continuous strips, a vertically 100 slideable member, a spring to control said member, a spring controlled pawl on the slideable member adapted to engage the cap strip, to feed the caps, when moved in one direction and to slide freely over them in the other direction, a hammer for firing the 105 caps, a spring controlling this hammer, a spring controlled plunger in the barrel of the gun, a handle connected to the plunger, a slot in the body or casing and a recess in the end of this slot in which the handle on 110 the plunger engages, a rotatory cam-plate adapted to release the handle of the plunger from the recess in the slot in which it engages so as to eject a projectile after the feeding mechanism has been released and a 115 rotatable crank or cocking-handle adapted to operate the three mechanisms, a spindle to the cocking handle, a cam on this spindle, and a projection on the spring controlled hammer adapted to be engaged by the cam 120 to move the hammer to the firing position.

BERNARD OWEN.
